BY Edward F. Stoltz
ATTORNEY

UNITED STATES PATENT OFFICE

CARL A. PFUDERER, OF BROOKLYN, NEW YORK

BOOKMARK

Application filed September 19, 1928. Serial No. 306,880.

This invention relates generally to the art of indicating a page of reading after a book has been closed, and has more particular reference to a novel bookmark.

5 The invention has for an object, the provision of a device of the class mentioned which is of simple durable construction, desirable in use and efficient in action, and which can be manufactured and sold at a reasonable cost.

The invention has for a further object, the provision of a device of the class mentioned which is easily applied onto a book, and arranged in applied position for not interfering with the turning of the pages of the book or otherwise being in the way of a reader.

15 The invention proposes the use of a strip of material arranged for being supported substantially parallel with the top edges of the leaves of a book, substantially at the binding thereof and extending for a short distance towards the edge of the book, remote from the binding, and provided with a pivotally mounted marker arranged for swinging from a position engaged between the leaves of the book to an inoperative rest position upon the said strip. In the position of rest the marker is above the leaves, thus not interfering with the turning thereof, and 20 further not being in the way of a reader. Preferably the said strip is held in position as described by a clamp arranged for engaging the web of the cover of the book directly adjacent the binding. The device also presents various surfaces for accommodating ornamentation and advertising matter.

25 For further comprehension of the invention, and of the objects and advantages thereof, reference will be had to the following description and accompanying drawing, and to the appended claims in which the various novel features of the invention are more particularly set forth.

40 45 In the accompanying drawing, forming a material part of this disclosure:—

Fig. 1 is a fragmentary perspective view of a book with the book marker engaged thereon.

50 Fig. 2 is a fragmentary longitudinal ver-

tical sectional view, taken on the line 2—2 of Fig. 1.

Fig. 3 is an enlarged detailed fragmentary plan view of the end of the device upon which the marker engages.

55 Fig. 4 is a vertical sectional view, taken on the line 4—4 of Fig. 3.

Fig. 5 is a perspective view of the marker, per se.

60 Fig. 6 is a bottom view thereof, showing portions thereof twisted for engaging the marker on the end of the device shown in Fig. 3.

65 Fig. 7 is a perspective view of a marker constructed according to the same invention but of modified form.

Fig. 8 is a vertical sectional view of a marker constructed according to further modified form, and

70 Fig. 9 is a perspective view of a marker of still further modified form.

75 The reference numeral 10 indicates generally the leaves of a book having a binding 12, covers 13, and a cover web 14 directly adjacent the binding 12. A book marker 15 is shown engaged on the web 14.

80 The book marker 15 comprises a strip of material 16, preferably of celluloid, arranged for being supported substantially parallel with the top edges of the leaves 10 by reason of being formed with a downwardly bent end 17 for engaging the outside of the web 14, and disposed laterally and coacting with a clamp tongue 18 for engaging on the inside of the web 14. The clamp tongue is preferably made 85 of celluloid and has an integral lug 19 positioned beneath the strip 16 and secured thereto by eyelets 20. The lower portions of the ends 17 and 18 are pointed as indicated by numeral 21 for aiding in the operation of 90 engaging upon the web 14.

95 The free end of the strip 16 is formed with an aperture 22 aligned with a slot 23 formed in the free end of the lug 19. A marker 24 has a rear end formed with an aperture 25 and is pivotally mounted on the material of the strip 16 between the aperture 22 and the free end thereof, this being clearly shown in Fig. 2. The rear end of the marker 24 is formed with a cut 26 communicating with 100

- the aperture 25 so that the material of the marker may be twisted as indicated by dot dash lines 27 in Fig. 5 and full lines in Fig. 6 for permitting engagement on the strip 16.
- 5 A marker guide member 24^a is pivotally mounted on one of the eyelets 20, and has a pair of integral guide arms 24^b spaced from each other at substantially a distance equal to the thickness of the marker 24. These arms 10 engage against the sides of the marker for guiding it in its pivotal movements. This arrangement permits the marker to be turned slightly laterally for engaging between the leaves at the beginning or end of the book.
- 15 The modified form of the device illustrated in Fig. 7 discloses an advertising placard 28 cemented on the top of the strip 16 for covering the eyelets 20. Also an ornamented initial 29 is shown secured on the device for 20 representing the initial of the owner thereof.
- In Fig. 8 a modified form of the device has been disclosed in which the strip 16 and the lug 19 are secured together by cement 30 therebetween. An eyelet 20 is shown engaged 25 thru the strip 16 for pivotally holding the marker guide member 24^a for reasons previously described relative to Figs. 2, 3 and 4.
- In Fig. 9 a modified form of the device has been disclosed in which the strip 16 has a 30 coiled free end 31 supporting a pintle pin 32 and the marker 24 is pivotally mounted on the pintle pin 32. Also the strip 16 has a down-turned end 17^a formed with a stamped out tongue 33. This device may be engaged upon 35 the cover web of a book by end 17^a engaging on one side of the web and tongue 33 on the other side.
- In operation of the device, it is engaged 40 on the web portion of the cover of a book so that the strip supporting the marker extends a short distance away from the binding of the book, and the marker is turned so as to rest upon the strip, as indicated by dot dash lines 34 in Fig. 2. In this position of 45 the marker the leaves of the book may be turned, and the book very comfortably read, that is the book may be tilted at various reading angles as desired by the reader without the marker moving out of place. Upon inter- 50 ruption of reading, the marker 24 may be moved off of the strip and extended downwards between the leaves of the book for keeping the reader's page and allowing a closing of the book.
- 55 The mentioning that certain of the parts of the marker should preferably be made of celluloid is not a limitation. These parts can be made of any other spring material, whether it be of fiber or metal.
- 60 While I have illustrated and described my invention with some degree of particularity, I realize that in practice various alterations therein may be made. I therefore reserve the right and privilege of changing the form 65 of the details of construction or otherwise

altering the arrangement of the correlated parts without departing from the spirit or the scope of the appended claims.

Having thus described my invention, what I claim as new, and desire to secure by United States Letters Patent is:—

- 70 1. A bookmark, comprising a strip formed with a bent end for engaging the outside of the web of a book cover, a clamp tongue disposed laterally of the said bent end for engaging the inside of the same web, a lug integral with the clamp tongue and attached on the said strip, and a marker pivotally mounted on the free end of the strip and arranged for extending downwards or assuming a 75 position of rest upon the strip.
- 80 2. A bookmark, comprising a strip formed with a bent end for engaging the outside of the web of a book cover, a clamp tongue disposed laterally of the said bent end for engaging the inside of the same web, a lug integral with the clamp tongue and attached on the said strip, and a marker pivotally mounted on the free end of the strip and arranged for extending downwards or assuming a 85 position of rest upon the strip, the extremities 90 of the said bent end and clamp tongue being pointed for ease in engaging upon a web.
- 95 3. A bookmark, comprising a strip formed with a bent end for engaging the outside of the web of a book cover, a clamp tongue disposed laterally of the said bent end for engaging the inside of the same web, a lug integral with the clamp tongue and attached on the said strip by eyelets passed thru the said 100 parts, and arranged for extending downwards or assuming a position of rest upon the strip.
- 105 4. A bookmark, comprising a strip formed with a bent end for engaging the outside of the web of a book cover, a clamp tongue disposed laterally of the said bent end for engaging the inside of the same web, a lug integral with the clamp tongue and attached on the said strip, the said strip being formed 110 with an aperture, the said clamp tongue being formed with a slot aligned with the said aperture, and a marker pivotally mounted on the strip thru the said aperture, and guided in its movements by a pivotally mounted marker guide and arranged for extending downwards or assuming a position of rest upon the said strip.
- 115 5. A bookmark, comprising a strip formed with a bent end for engaging the outside of the web of a book cover, a clamp tongue disposed laterally of the said bent end for engaging the inside of the same web, a lug integral with the clamp tongue and attached on the said strip, and the said strip being formed 120 with an aperture, and said clamp tongue being formed with a slot aligned with the said aperture, and a marker pivotally mounted on the strip thru the said aperture, and arranged 125 for extending downwards or assuming a position of rest upon the said strip.

sition of rest upon the said strip, a marker guide member pivotally mounted and formed with guide arms engaging against the sides of the marker, the said marker having a cut communicating with its pivotal point for permitting bending during the period of being pivotally positioned.

6. A bookmark, comprising a strip formed with a bent end for engaging the outside of the web of a book cover, a clamp tongue disposed laterally of the said bent end for engaging the inside of the same web, a lug integral with the clamp tongue and attached on the said strip by eyelets passed thru the said parts, a marker pivotally mounted on the free end of the strip and arranged for extending downwards or assuming a position of rest upon the strip, and a placard attached on top of the strip for covering the eyelets.

10 7. A bookmark, comprising a strip formed with a bent end for engaging the outside of the web of a book cover, a clamp tongue disposed laterally of the said bent end for engaging the inside of the same web, a lug integral with the clamp tongue and attached on the said strip by cement disposed between the said parts, and a marker pivotally mounted on the free end of the strip and arranged for extending downwards or assuming a position of rest upon the strip.

15 Signed at New York, in the county of New York and State of New York, this 14th day of September, 1928.

CARL A. PFUDERER.
